UNITED STATES PATENT OFFICE.

LAYTON WATTON TOWNSEND, OF HAMILTON, ONTARIO, CANADA.

FOLDING SUIT-HANGER.

1,349,022.

Specification of Letters Patent. Patented Aug. 10, 1920.

Application filed February 12, 1920. Serial No. 358,281.

To all whom it may concern:

Be it known that I, LAYTON WATTON TOWNSEND, of the city of Hamilton, in the county of Wentworth, Province of Ontario, 5 Dominion of Canada, have invented certain new and useful Improvements in Folding Suit-Hangers, of which the following is the specification.

My invention relates to improvements in 10 folding suit hangers and the object of the invention is to devise a hanger of this type which can be folded into very small space for shipping or packing and which will be very cheap to make; a further object is to 15 make a hanger of such form that it can be shipped in the knock down position and can be easily and quickly assembled for use without any tools.

My invention consists of a horizontal 20 member, and two inclined members pivotally mounted on the horizontal member near the ends thereof and a supporting hook passing through engaging orifices in the free ends of the inclined members, all as 25 more particularly described and illustrated in the accompanying drawing, in which:

Figure 1 shows my hanger in the assembled form.

Fig. 2 shows the hanger partially folded. 30 Fig. 3 is a top view of the hanger in the folded form.

Fig. 4 is a side view thereof.

Fig. 5 is a front view of the supporting hook; and Fig. 6 is a side view thereof.

Like characters of reference indicate 35 corresponding parts in the different views.

1 is the horizontal member. 2 and 3 are the inclined side members. 4 and 5 are nails or rivets pivotally connecting the members 40 2 and 3 to the member 1. 6 and 7 are orifices extending through the members 2 and 3 near their upper ends and adapted to register with each other. 8 is the supporting hook which has the upper hook portion 9 and the lower hook portion 10 disposed at 45 right angles to each other.

My hanger is constructed as follows:

When constructed in the factory the inclined members 2 and 3 are pivotally 50 mounted to the member 1 by means of the nails or rivets 4 and 5, and the orifices 6 and 7 are made in the members 2 and 3. The

lower hook portion 10 is left open as shown in Fig. 6, and the hanger is shipped in the folded position as shown in Figs. 3 and 4 with the hook detached. All that is necessary in assembling the hangers for use is to pass the hook portion 10 through the orifices 6 and 7 which secures the hanger in the open position. When open the hanger 60 is in triangular form with the apex uppermost. The hook portion 10 can be closed in by the thumb after being inserted in position so that it cannot become disengaged.

It will be noted that all the arms of my 65 hanger are of simple straight pieces of wood and are not in any way shaped. The two side arms 2 and 3 are identical in form and are made from a rough block by simply drilling the end holes then cutting on a 70 multiple saw. The horizontal member 1 is similarly made.

No planing is necessary as the rough sawed pieces are simply smoothed in a 75 tumbler device.

The chief advantages of my hanger reside in the very small space which it occupies when being shipped or stored and with the simplicity and cheapness of construction. It is particularly suitable for what 80 are called give-away hangers which are so extensively used as an advertising means for tailors, dress-makers, etc. Any desired advertising matter may be printed on the flat sides of the members.

From the foregoing it will be seen that I have devised a very simple and useful suit hanger.

What I claim as my invention is:

A folding suit hanger comprising three 80 straight members, two of said members being of equal length and shorter than the third member, the shorter members being pivotally connected at one end to the third member adjacent its ends and on opposite 95 sides thereof, a hook member pivotally connecting the free ends of the shorter members, and the three members being adapted to fold in parallelism with each other upon removal of the hook for a purpose specified. 100

LAYTON WATTON TOWNSEND.
